ATTORNEY.

UNITED STATES PATENT OFFICE

SAMUEL J. PALMER, OF SAN MATEO, CALIFORNIA

COLLAR

Application filed January 29, 1929. Serial No. 335,926.

This invention relates to improvements in soft and semi-soft shirt collars of the present popular attached and unattached types, the main purpose being to provide a simple and efficient means for holding the points of the collar down close to the shirt front, and to maintain the collar in proper position and in its best appearance at all times.

An object of the invention is to provide a collar of the character described in which the means for holding the collar points and ends in proper position may be readily and easily fitted to or removed from the collar, said means being inexpensive, in one piece form and requiring but a slight change in the construction of the collar to permit of attachment thereof to the collar.

Another object is to provide a collar of the character described in which the point retaining means will securely remain in place after being fitted to the collar and will not interfere with the placing and adjusting of a necktie, the necktie in fact, acting to aid said means in holding the collar point down close to the shirt front.

A further object is to provide a collar as described in which the collar point retaining means are in the form of V-shaped pieces of suitable resilient material such as will be comparatively stiff and yet have a slight flexibility; the collar being so constructed as to provide spaced but opposed retaining elements on the neck band and outer fold respectively, into proper engagement with which elements the V-shaped pieces may be easily and quickly placed without necessitating the bending or the flexing of said elements out of their normal V-shaped form.

A still further object is to provide means of the character described which will not be unsightly or prove uncomfortable to the wearer, said means being entirely concealed when in position.

With the above and other objects in view the invention consists in the novel construction and combination of parts herein-after described, illustrated in the accompanying drawings and set forth in the claims hereto appended, it being understood that various changes in the form, proportion, size

and in minor details of construction within the scope of the claims may be resorted to without departing from the spirit or sacrificing any of the advantages of the invention.

Referring to the drawings, Fig. 1 is a top plan view of the collar of this invention as when opened, and showing the device of my invention partly in position,

Fig. 2 is a perspective view of the collar of this invention showing in dotted lines the point retaining means in position of use,

Fig. 3 is a cross sectional view taken thru the collar and showing said point retaining means in position of use,

Fig. 4 is a perspective view of both point retaining devices,

Fig. 5 is a fragmentary plan view of a modified form of the invention,

Fig. 6 is a cross-sectional view of the collar shown in Fig. 5.

The embodiment of my invention shown in detail in the accompanying drawings includes a soft collar having the usual neck band 1, outer fold 2 and points or ends 3. Along the inner side of the outer fold 2, I provide in any suitable manner elongated pockets 4 which pockets extend close to and parallel to the end edges of said outer fold for substantially the full length of the points 3. The outer ends of these pockets are closed and the inner ends are open at points near the fold line.

Opposite and in line with these pockets, but located on the neck band 1 are retaining elements in this instance in the form of tunnel loops 5. These loops may be formed by sewing strips 6 of cloth to the neck band or, as shown in Figs. 5 and 6, may be made by cutting slits or button holes 7 in the outer ply of the neck band.

V-shaped pieces 8 are provided for insertion into the pocket 4 and tunnel loops 5. These pieces 8 are formed of any suitable stiff but slightly flexible material, such as spring steel. One leg of each V piece is longer than the other leg and is adapted to be placed in one of the pockets 4 and to extend close to the tip of the collar point and substantially parallel to the slanting edges of the outer fold. The shorter legs of these V pieces are adapted to extend under and be entirely cov-

ered by the tunnel loops 5. These shorter legs are laterally offset to provide for proper conformation of the pieces 5 to the collar and neck band, which latter are angularly related when the collar is in place. These pieces 8 are of less width than the pockets 4 and loops 5 in which they are inserted so that said pieces may adjust themselves to proper position and conformation dependent on the collar and the size of the necktie. The ends of the longer legs are formed with rounded points so as to extend close to the tips of the points of the collar and prevent said tips from turning upwardly.

15 To insert the V pieces 8, the collar is opened as shown in Fig. 1 and the longer legs are inserted thru the tunnel loops 5 and into the pockets 4 as shown in Figs. 1 and 5. Then the collar is turned over and the V pieces are pushed further into place so that the shorter legs will be covered by the tunnel loops and both legs will be brought to position shown in Figs. 2, 3 and 4. This operation of inserting the V pieces into place does not necessitate the bending or the flexing of the said pieces out of their normal V-shaped form. This is important for if the said V pieces had to bend or flex out of normal shape to insert therein said pieces would not return to proper 20 position necessary to insure the holding of the points down close to the shirt front. These pieces 8 must be comparatively stiff in order to accomplish the purpose of the invention, and to provide such stiffness I must use spring 25 steel or similar metal and "thread", that is, insert the pieces thru the loops 5 and into the pocket without bending or appreciably flexing the said pieces out of shape.

When the necktie is in place it lies over 30 the shorter legs of the V pieces and presses thereon so as to force the longer legs downward toward the shirt front and then together with the points of the collar in such 35 positions. The loops cover said legs and prevent interference with the necktie in adjusting said tie.

The usual stitching along the edges of the outer fold of the collar points serves as a means of fastening the pocket forming strips 40 of cloth to said outer fold.

I claim:—

1. A collar having a neck band and an outer fold, pockets on the inner side of the outer fold thereof, which pockets are close to the 45 end edges of said outer fold and extend from near the juncture of said fold with the neck band to near the outer points of said outer fold, loops on the neck band and in line with the pockets, and permanently V-shaped flexible pieces which are inserted thru the loops and into said pockets, the legs of which pieces lying in said pockets and under said loops, respectively.

60 2. A collar of the character described comprising a neck band, an outer fold carried by

the neck band, pockets on the inner sides and at the ends of said outer fold, permanently V shaped members having the legs thereof laterally twisted out of opposed relation and loops on the neck band through which the V shaped members are insertable into and out of said pockets.

In testimony whereof I affix my signature.
SAMUEL J. PALMER.
